United States Patent Office

Des. 184,282
Patented Jan. 20, 1959

184,282

PUFFED TEXTILE FABRIC

Henry E. Goforth, Winnsboro, S. C., assignor to United States Rubber Company, New York, N. Y., a corporation of New Jersey

Application February 19, 1958, Serial No. 49,710

Term of patent 14 years

(Cl. D92—1)

FIG. 1

FIG. 2

Fig. 1 is a plan view of a puffed textile fabric showing my new design; and

Fig. 2 is a schematic sectional view of the fabric of Fig. 1 along the line 2—2.

I claim:

The ornamental design for a puffed textile fabric, as shown.
